The design for the airborne vehicle air frame, as shown and described.

DESCRIPTION

FIG. 1 is a top view of an airborne vehicle air frame.

FIG. 2 is a bottom view of the airborne vehicle air frame shown in FIG. 1.

FIG. 3 is a right side view of the airborne vehicle air frame shown in FIGS. 1 and 2.

FIG. 4 is a left side view of the airborne vehicle air frame shown in FIGS. 1-3.

FIG. 5 is a back side view of the airborne vehicle air frame shown in FIGS. 1-4.

FIG. 6 is a front side view of the airborne vehicle air frame shown in FIGS. 1-5.

FIG. 7 is a top view of an airborne vehicle air frame.

FIG. 8 is a bottom view of the airborne vehicle air frame shown in FIG. 7.

FIG. 9 is a right side view of the airborne vehicle air frame shown in FIGS. 7 and 8.

FIG. 10 is a left side view of the airborne vehicle air frame shown in FIGS. 7-9.

FIG. 11 is a back side view of the airborne vehicle air frame shown in FIGS. 7-10; and,

FIG. 12 is a front side view of the airborne vehicle air frame shown in FIGS. 7-11.
